UNITED STATES PATENT OFFICE

JOHN MILARSKI, OF PATERSON, NEW JERSEY

DESIGN FOR A CURTAIN ROD BRACKET

Application filed September 5, 1930. Serial No. 36,883. Term of patent 7 years.

To all whom it may concern:

Be it known that I, JOHN MILARSKI, a citizen of Poland, residing at Paterson, in the county of Passaic and State of New Jersey, have invented a new, original, and ornamental Design for Curtain Rod Bracket, of which the following is a specification, reference being had to the accompanying drawings, forming part thereof.

Figure 1 is a front elevation of a curtain rod bracket showing my new design, and Figure 2 is an edge view of the curtain rod bracket shown in Figure 1.

The back of the hanger fixture is plain.

I claim:

The ornamental design for a curtain rod bracket, as shown and described.

JOHN MILARSKI.
